(57) **CLAIM**

We claim the ornamental design for a probe for ultrasound diagnostic apparatus, as shown.

DESCRIPTION

FIG. 1 is a front view of a probe for ultrasound diagnostic apparatus showing my new design.

FIG. 2 is a front-side elevational view thereof;

FIG. 3 is a rear-side elevational view thereof;

FIG. 4 is a left-side elevational view thereof;

FIG. 5 is a right-side elevational view thereof;

FIG. 6 is a top-side elevational view thereof; and,

FIG. 7 is a bottom-side elevational view thereof.
